UNITED STATES PATENT OFFICE.

CLARENCE E. LEFFEL, OF MEADVILLE, PENNSYLVANIA, ASSIGNOR TO THE SPIRELLA COMPANY, OF MEADVILLE, PENNSYLVANIA, A CORPORATION OF PENNSYLVANIA.

ELECTROPLATING-RACK.

1,010,648.

Specification of Letters Patent. Patented Dec. 5, 1911.

Application filed June 26, 1909. Serial No. 504,448.

To all whom it may concern:

Be it known that I, CLARENCE E. LEFFEL, a resident of Meadville, in the county of Crawford and State of Pennsylvania, have invented a new and useful Improvement in Electroplating-Racks, of which the following is a specification.

This invention relates to racks or hangers for use in electroplating metal articles, and more particularly to cathode hangers for electroplating.

In electroplating all bare metallic surfaces connected with the cathode and immersed in the bath or solution receive a deposit of the metallic and consequently the metallic supports which hold the work or convey the current become heavily coated. This coating is practically wasted or, at least has to be recovered at considerable expense, and in addition to this its deposition involves a wasteful consumption of current.

The object of my invention is to reduce to a minimum the bare surface of the rack outside of that necessary to make a proper electrical contact with the article to be plated. It also provides for holding all parts of the work to be plated practically equidistant from the anode so that all portions of the article are uniformly coated.

The invention comprises a rack constructed and arranged as hereinafter described and claimed.

In the accompanying drawing, Figure 1 is a sectional view of a portion of an electroplating tank showing one of the racks in position; Fig. 2 is an end view of the rack; and Fig. 3 is a side elevation thereof.

In the drawings, the electroplating tank is shown at 1 and the cathode conductor at 2. The anode is not shown, but preferably there will be two, one on each side of the cathode, as will be readily understood by those skilled in the art.

The rack comprises two similar side members 3 and cross-connecting members 4. Each side member comprises a body 5 of non-conducting material, such as wood, although if desired it may be fiber, porcelain or other non-conducting material. The cross-connecting parts 4 are shown in the form of metal rods passing through holes in the two side member bodies and receiving nuts 6 on their outer ends. Suitably connected to each body 5 is a hanger 7 in the form of a brass or copper hook for ready

attachment to or detachment from the cathode conductor 2. On each side face of the body 5 is a member 8 serving as a conducting support for the article, these being in the form of strips of copper, brass or other good conducting material and having the article supports provided by bending the same to form projections 9, preferably inclined upwardly. These members 8 are connected to the hooks 7 in a manner to give a good electric connection, such as by means of rivets 10, and are detachably connected to the insulating body 5, such as by means of nails or screws 11. Consequently, when they become excessively coated, they can be readily removed and be replaced by new strips.

The articles to be plated are laid upon the projections 9 of the two side members. The projections on the same side of the rack are in line with each other, while, preferably, arranged in alternate relation with those on the opposite side of the rack, as shown.

The rack described provides for holding all articles a uniform distance from the anode in a manner to practically expose all parts of the article and secure a uniform coating. The construction is such that when the article supporting members are excessively coated they can be replaced at a very low cost for labor and material.

What I claim is:

1. A cathode hanger for electro-plating, comprising a non-conducting body, a conducting hanger therefor, and a conducting support detachably connected to the body, and electrically connected to the hanger, the said support comprising a conducting strip provided with a plurality of integral supporting projections.

2. A cathode hanger for electro-plating comprising a non-conducting body, a conducting hanger therefor, and a conducting strip detachably connected to the body and electrically connected to the hanger, said conducting strip being provided with a series of work supporting projections in permanent and intimate electrical connection therewith.

3. A cathode hanger for electroplating, comprising a non-conducting body and a conducting hanger therefor, and a conducting strip bent to provide a series of supporting projections detachably connected to the

body and electrically connected to the body and electrically connected to the hanger.

4. A cathode hanger for electro-plating, comprising a pair of members each comprising a non-conducting body, a conducting hanger therefor, and conducting supports detachably connected to the body and electrically connected to the hanger, and cross members connecting said non-conducting bodies.

5. A cathode hanger for electro-plating, comprising a non-conducting body, and a contact strip detachably secured thereto and provided with a plurality of integral work supporting projections.

15 6. A cathode hanger for electroplating,

comprising a pair of oppositely arranged conducting strips bent to provide a series of supporting projections, and a suitable support for said strips.

7. A cathode hanger for electro-plating, comprising oppositely arranged conducting strips bent to provide a series of supporting projections, and a suspending member connected to the upper ends of said strips.

20 25 In testimony whereof, I have hereunto set my hand.

C. E. LEFFEL.
